UNITED STATES PATENT OFFICE.

GEORGE S. SOWERS, OF SPRING HILL, KANSAS.

COMBINED GRAIN, STOCK, AND PLAIN RACK WITH STOCK-CHUTE.

1,322,068.

Specification of Letters Patent. Patented Nov. 18, 1919.

Application filed April 13, 1918. Serial No. 228,481.

To all whom it may concern:

Be it known that I, GEORGE S. SOWERS, a citizen of the United States, residing at Spring Hill, in the county of Johnson and 5 State of Kansas, have invented certain new and useful Improvements in Combined Grain, Stock, and Plain Racks with Stock-Chutes, of which the following is a specification.

10 This invention relates to agricultural implements and more particularly to a portable and convertible grain and stock rack.

The primary object of this invention resides in the provision of a portable and convertible grain and stock rack of such construction that the grain pitcher usually employed to load the rack will be dispensed with.

15 A further object of this invention resides in the provision of a portable grain rack which consists of a certain embodiment of elements that can be readily adjusted to accommodate certain portions of the contents of the rack as it is being loaded.

20 A still further object of this invention resides in the provision of a portable grain rack that can readily be converted into a stock rack with a stock chute detachably secured thereto.

25 With these and other objects in view this invention resides in certain novel features of construction and combination of elements which will hereinafter be more fully set forth in the specification and pointed out 30 in the appended claim, it being understood that the right is reserved to resort to any change in detail as comes within the scope of the claim.

In the accompanying drawing:—

35 Figure 1 is a side view of a portable grain rack constructed in accordance with this invention with the near side thereof partially assembled;

40 Fig. 2 is a rear view thereof showing the rack completely assembled;

45 Fig. 3 is a detail perspective view of a portion of the rear end of the rack with the stock chute thereon;

50 Fig. 4 is a sectional view on line 4—4 of Fig. 1;

55 Fig. 5 is a detail perspective view of one of the side board retaining pins;

Fig. 6 is a similar view of one of the mortise irons.

55 In the present embodiment of this inven-

tion the numeral 5 designates the grain rack which consists of a floor 6 supported on beams 7 that are in turn secured to a running gear 8 of any approved construction.

Securely fastened to the floor 6 of the 60 rack are end standards 10 and side standards 12, the former of which are preferably secured by brackets 14 for permanent occupation of their initial positions while the latter are removably secured to the floor and 65 braced by brackets 16 in order that they may be removed.

Fastened to the end standards 10 are spaced boards 18 which form the ends of the 70 rack.

Hingedly secured as at 20 to the rear end of the rack is a gate 22 that is constructed to form the floor of a stock chute when in its lowered position. This end gate is retained in elevated position by fastening elements 24 of any approved type but in this instance hooks and eyes are employed. Secured to the opposite sides of the gate or floor of the chute are mortise irons 26 that are adapted to receive the projecting ends 28 80 of the standards 29 that support the side boards 30 of the stock chute. The aforesaid side boards are provided with hooks 32 which are employed to hang the side boards on the side of the rack while in transportation and 85 thus retain them in a convenient position for their access.

This gate is of such length that it terminates on a line with the top of the rear end of the rack and when lowered to abut the 90 gate of the stock yard it assumes a slight incline if the rack is mounted on small wheels but where the wheels of the rack are large, this gate will be proportionately larger and will extend above the rear end 95 of the rack while in raised position.

Secured by screws 34 or the like to said standards 12 are the bases 36 of pins 38. The pins 38 are adapted to be inserted through apertures 40 in said standards 100 with a sufficient portion projecting beyond the outer face of each standard to accommodate the side boards 42 of the rack when secured thereon by the pegs 44 which are inserted in slots 46 formed near the outer 105 end of each pin.

In order to retain the entire series of side boards 42 in a convenient position of access, the lowermost pins 38 are made much longer than the others and are provided with slots 110

48 adjacent their intermediate portions to retain the series of boards thereon in a secured position.

As the rack is being loaded it is only necessary to secure that board in position which would retain a portion of the entire load, and since it is necessary to have the entire collection of elements in a convenient position, pegs 44 are fastened on the ends 10 of chains 50 or the like.

Supported by the bottom of the rack at opposite sides thereof are steps 52 which are adapted to be folded and retained against the sides of the rack by chains 54 or the like which have pegs 56 secured to their free ends for engagement with eyes, 58. These steps readily enable the loader to climb in and out of the rack to distribute the grain in an even condition during the 20 loading.

When the season for loading grain has passed, the center standards can be detached from the floor of the rack and the remaining standards will support the end of the 25 rack to enable the hauling of various articles.

With this invention herein set forth it is apparent that a rack has been produced which embodies an assemblage of elements that are cheap of manufacture and readily adaptable in attaining the maximum efficiency with a minimum amount of labor. 30

Having thus described this invention what I claim is:

A stock rack including in combination, a 35 floor, and standards fixed to said floor, side standards secured to said floor, a plurality of aligned supporting pins secured to each of said standards a plurality of spaced side boards held on said pins, each of said pins 40 having a base and an aperture the lowermost of said supporting pins being of a length to receive all of said side boards in one position, and a pin in each of said apertures, whereby said side boards are removably 45 held, as and in the manner shown.

In testimony whereof I affix my signature.

GEORGE S. SOWERS.
